METHOD OF AND APPARATUS FOR BURNING
Anthony I. Osswald, 66 Inter Park Ave., Buffalo, N.Y.
Filed Nov. 18, 1958, Ser. No. 774,619
1 Claim. (Cl. 110—8)

This invention relates to an incinerator.

The object of the invention is to provide an incinerator which is adapted to be used for burning trash, garbage or the like, so that the products of combustion leaving the incinerator will be substantially free of odor, impurities, and the like.

Another object of the invention is to provide a method of and apparatus for burning trash and the like wherein the final products of combustion leaving the incinerator are substantially free of impurities such as carbon since a highly effective and novel means is provided for insuring that complete combustion takes place.

A further object of the invention is to provide an incinerator which is extremely simple and inexpensive to manufacture.

Other objects and advantages will be apparent in the course of the following description.

In the accompanying drawings, forming a part of this application, and in which like numerals are used to designate like parts throughout the same.

FIGURE 1 is an end elevational view of the incinerator of the present invention.

FIGURE 2 is a side elevational view of the incinerator.

FIGURE 3 is a horizontal sectional view taken through the incinerator.

FIGURE 4 is a vertical sectional view taken through the incinerator.

FIGURE 5 is a sectional view taken on line 5—5 of FIGURE 4.

Referring in detail to the drawings, the numeral 10 indicates the incinerator of the present invention which is shown to comprise an outer hollow housing 11, and the housing 11 includes a horizontally disposed bottom wall 12, spaced parallel end walls 13 and 14, and the housing 11 further includes an arcuate top wall 16 which is provided with an air inlet 15.

The numeral 17 indicates a horizontally disposed grate, and the numeral 18 indicates a hollow casing which is arranged within the housing 11. The casing 18 includes spaced parallel vertically disposed end walls 19 and 20, as well as spaced parallel vertically disposed side walls 21 and 22 and an arcuate top wall or member 23. The members or walls of the casing 18 are spaced inwardly from the walls of the housing 11 so as to define an air space 24, and the inlet air opening 15 communicates with the space 24, so that the air can be preheated as later described in this application, and this preheated air is adapted to be used for supporting combustion in the incinerator. The numeral 25 indicates slots or openings which permit the air from the passageway 24 to enter the bottom of the incinerator.

There is defined within the incinerator an upper chamber 26 and a lower chamber 27. The numeral 28 indicates a generally horizontal baffle which has one end spaced from the end member 20 of the casing 18, as for example as shown in FIGURE 4 so that the products of combustion from the lower chamber 27 can pass through the opening 29 and enter an approximately L-shaped passageway 31 that is used for the products of combustion. The passageway 31 is defined between the baffle 28 and a partition 30, and the numeral 32 indicates a generally vertical portion which has its lower end communicating with the horizontal portion of the passageway 31.

Arranged in communication with the lower chamber

2

27 is a plurality of burners 33 which may be of conventional construction and which may be supplied with fuel from a suitable source of supply. There is further provided a burner 34 which is arranged contiguous to the upper end of the portion 32 of the passageway 31, and the upper burner 34 communicates with the upper chamber 26 in the incinerator. The numeral 35 indicates a flue which extends through the wall 14 of the housing 11 and communicates with the interior of the upper chamber 26 as shown in FIGURE 4. The numeral 36 indicates an opening or inlet through which trash, garbage or the like can be inserted into the chamber 27, and a door 37 is mounted to move into and out of closed relation with respect to the opening 36. Thus, when trash is to be burned, the door 37 is to be moved to open position and then the door 37 can be closed.

The housing 11 further includes vertically disposed side walls 38 and 39, which are spaced outwardly from the side members 21 and 22 of the inner casing 18 where- 20 by the previously described air passageways 24 are provided.

From the foregoing, it is apparent that there has been provided a method of and apparatus for burning trash, garbage or the like. In use, the trash or other material 25 to be burned is adapted to be loaded into the lower chamber 27 through the opening 36, it being understood that the door 37 is first moved to open position and after the trash has been inserted into the chamber 27 the door 37 is closed. The burners 34 and 33 are adapted 30 to be actuated or energized and these burners may be gas fired or electrically operated and it is to be noted that the grate 17 provides a support for the trash which is being burned up. With the burners 33 functioning or operating it will be seen that the trash in the chamber 27 35 will be ignited and the exhaust gases or products of combustion from this ignition will pass up to the opening 27 and these products of combustion will then pass through the horizontal portion of the passageway 31, and then to the vertical portion 32. In the event that the products 40 of combustion contain impurities or carbon which has not been fully burned, the secondary burner 34 will further ignite these products in the chamber 26, so that the waste gases which pass out through the flue 35 will be free of carbon or the like so that the waste gases will not contain any odors or other impurities.

The air for supporting combustion enters the incinerator through the opening 15, and this air then passes down through the spaces 24. It is to be noted that the parts are arranged so that this air passes downwardly 50 in heat exchange contact with the inner casing 18 so that the incoming air will pick up some of the heat from the inner casing whereby the air will be preheated. This preheated air will then pass through the slots 25 and up through the grate 17 so as to support the combustion. 55 Since the air is preheated, the incinerator will be able to operate more efficiently.

Thus, it will be seen that there has been provided a lower zone in which the trash, garbage or the like is first burned, and wherein there is further provided an upper 60 zone 26 wherein the products of combustion resulting from the burning in the lower zone are exposed to the action of a secondary burner 34 and this insures that the waste gases passing out through the flue 35 will be practically free of any carbon like material which has a tendency to cause smoke that is obnoxious to smell or view or breathing in.

The parts can be made of any suitable material and in different shapes or sizes.

Suitable baffles can be used wherever desired or required, and a suitable means can be provided for emptying the incinerator of ashes. The incinerator can be used in industrial locations, or else it can be used for domestic

installations. The burners may operate on a suitable fuel such as oil, gas, or the like, or else they may be electrically operated.

The incinerator can be used for burning any type of material and the incinerator is especially suitable for burning carbon containing material of a high burning point. Since the waste gases which pass out through the flue 35 will be practically odorless and colorless, the incinerator is especially suitable for use around buildings, homes, and the like, since the air will not become polluted, and clothes which may be hanging on clotheslines or the like will not become contaminated. The heat from the burning process is transferred to the incoming air so that the preheated air can make the process more efficient.

The device is ruggedly constructed and consists of a minimum number of parts and requires no manipulation during the use thereof. It will be seen that there has been provided an apparatus and process of burning wherein combustible materials can be burned in such a manner so that smoke and obnoxious odors are prevented from contaminating the atmosphere. The incinerator can be used for burning any suitable type of material.

Minor changes in shape, size and rearrangement of details coming within the field of invention claimed may be resorted to in actual practice, if desired.

I claim:

In an incinerator, a hollow housing including a horizontally disposed bottom wall, spaced parallel vertically disposed side walls, spaced parallel vertically disposed end walls, and an arcuate top wall; a horizontally disposed grate arranged in the lower portion of said housing, a casing arranged within said housing, said casing includ-

ing spaced parallel vertically disposed side walls and spaced parallel vertically disposed end walls, said casing further including a curved top member, there being air spaces between said casing and housing; a flue extending through said housing and communicating with the upper inner portion of the casing; an air inlet at the top of said housing communicating with said air spaces, a generally horizontal baffle arranged in said casing and having one end thereof spaced from a portion of the casing, a partition arranged above said baffle and coacting therewith to define an approximately L-shaped passageway that is used for the products of combustion, there being upper and lower chambers in said casing extending above and below said passageway, a generally vertical portion of the passageway establishing communication between a horizontal portion of said passageway and said upper chamber; said lower chamber communicating with the horizontal portion of said passageway, a plurality of spaced apart burners extending into said lower chamber, a burner extending into said upper chamber and positioned contiguous to said vertical portion of the passageway, one of said side walls having a trash inlet opening therein to said lower chamber, there being slotted openings in the side and end walls of said housing near the lower ends thereof for the egress therethrough of warm air into the lower chamber from the air spaces.
